UNITED STATES PATENT OFFICE.

JOSEPH W. SCHLOSS, OF NEW YORK, N. Y., ASSIGNOR TO JOSEPH W. SCHLOSS COMPANY,
A CORPORATION OF NEW YORK.

HAIR-WAVER.

1,320,099.

Specification of Letters Patent.

Patented Oct. 28, 1919.

Application filed January 13, 1919. Serial No. 270,797.

To all whom it may concern:

Be it known that I, JOSEPH W. SCHLOSS, a citizen of the United States, residing at the city of New York, in the borough of 5 Manhattan and State of New York, have invented certain new and useful Improvements in Hair-Wavers, of which the following is a full, clear, and exact description.

This invention relates to hair wavers, the 10 object being to provide a device of this character which, while being efficient and easy to manipulate, will be particularly cheap to manufacture. The hair waver in general belongs to that class which comprises a central body portion upon which the hair is wound and end portions which are afterwards folded down against the coiled hair to prevent it from uncoiling. My improved 15 waver embodies a core and a cover of suitable fabric, the invention residing more particularly in the construction of the core which consists of a middle or body portion elongated in shape and being of comparatively rigid construction, and a length of 20 wire which is attached at two points, respectively, to the two ends of the body portion, and thence leads outward in opposite directions. This wire, which is of pliable material, is connected with the stiffer body 25 portion in such a way as to render the device very cheap of manufacture.

In the accompanying drawings:

Figure 1 is a face view of the complete core of the hair waver;

Fig. 2 is an edge view of the same;

Figs. 3 and 4 are details of two modifications in the method of fastening the wire to the body portion of the core; and

Fig. 5 is a face view of the completed article.

The core of the waver comprises two parts, a middle body portion *a* and a length of wire *b*. The central body portion is preferably a metal or fiber plate, elongated and having rounded ends, and is so constructed in form or material that it will retain its original shape against such forces as may be applied to it in use. The wire *b*, on the other hand, is of pliable material and would 45 serve the purpose very well when made of lead. It is preferably a single length of wire which rests against one of the faces of the body portion *a* and is attached at two points respectively to the two extremities of the body portion. One way of mak-

ing this attachment is shown in Figs. 1 and 2. This consists in simply providing perforations *c*, *c*, at each end of the body portion through which the wire is loosely passed, the end portions of the wire extending in opposite directions for a distance slightly more than one-half of the length of the body portion. The passage of the wire through the two perforations creates kinks therein, which prevent longitudinal movement of the wire with respect to the body portion, no other fastening means being necessary. When the wire and body portion are assembled in the manner described, the core thus formed is passed 60 through a braiding machine and a cover of textile material is braided thereon from end to end, as shown in Fig. 5. In this braiding operation, the cover is shaped to closely fit the body portion and hug the 65 wire, thus giving the end portions of the waver the appearance and structure of a pliable cord. As a finish, hollow metal spheres *d* are applied to the extremities of the wire and cover. Instead of threading 70 the wire through the perforations *c*, as explained, a slit may be cut in each end of the body portion, as indicated at *e*, and extending from the perforation to the edge of the plate through which the wire can be laterally introduced into the perforation, or 75 if preferred, the mode of attachment shown in Fig. 4 can be used with considerable advantage. This consists in providing the ends of the body portion with two lateral ears 80 *f*, *f*, which are folded down upon the wire, clamping it against the face of the body portion. This plan permits of more than one wire being used, since two or more can be held under the ears as readily as a single 85 one. A plurality of wires extending side by side will afford more durability than a single wire of large size.

In using the waver, the hair is wound around the middle body portion and is held 90 in its coiled condition by bending the pliable terminal extensions inward against the hair. The nature of these clamping ends is to remain in any position to which they may be bent and they therefore serve as 95 clamps which can be readily closed and opened.

I claim:

1. A hair waver comprising a core consisting of an elongated body portion of 110

comparatively rigid construction and a wire attached at two points to the respective ends of the body portion and extending beyond each of said ends, in combination 5 with a cover inclosing the entire core.

2. A hair waver comprising a core consisting of an elongated body portion of comparatively rigid construction and provided with a perforation at each end, and a 10 wire threaded through said perforations and extending along the face of the body portion and some distance beyond each end thereof, in combination with a cover inclosing the core from end to end.

3. A hair waver comprising a core consisting of an elongated body portion of comparatively rigid construction and provided with a perforation at each end and with a lateral cut leading from each perforation to the edge, and a wire threaded 15 through said perforations and extending along the face of the body portion and some distance beyond each end thereof, in combination with a cover inclosing the core from end to end.

20 In witness whereof, I subscribe my signature.

25 JOSEPH W. SCHLOSS.
